GAUGING AND MARKING INSTRUMENT FOR DRAWER PULLS AND DOOR HANDLES

Filed June 13, 1939

UNITED STATES PATENT OFFICE

2,203,992

GAUGING AND MARKING INSTRUMENT FOR
DRAWER PULLS AND DOOR HANDLES

Francis Lutz, Merced, Calif.

Application June 13, 1939, Serial No. 278,809

8 Claims. (Cl. 33—189)

This invention relates generally to carpentry and more particularly to gauges and markers therefor.

An object of the invention is to provide an instrument facilitating the installation of builders' hardware and particularly adapted for use in gauging and marking drawers and cupboard and cabinet doors for pulls and handles, all in such manner as to expedite and simplify accurate installation of such hardware.

Another object of the invention is to provide an instrument of the above described character which is readily adjustable to accommodate drawers and doors of various sizes; can be securely locked in a selected adjusted position to insure uniform installation of the hardware on any number of drawers and doors desired; and can be arranged into a flat, compact parcel when not in use so as to require only a small space in a tool box.

With these and other objects in view, the invention resides in the combinations and arrangements of elements as set forth in the following specification and particularly pointed out in the appended claims.

25 In the accompanying drawing,

Figure 1 is a view showing in front elevation the instrument embodying this invention;

Figure 2 is a view of the instrument in side elevation;

Figure 3 is a view of the instrument in end elevation as viewed from the left of Figure 2;

Figures 4 and 5 are enlarged fragmentary sectional views, taken, respectively, on the lines 4—4 and 5—5 of Figure 2;

Figure 6 is a view of the instrument applied to the front of a drawer for the gauging and marking thereof for a single handle;

Figure 7 is a view similar to Figure 6, and illustrating the instrument applied to a drawer on which two handles are to be installed;

Figure 8 is a view of the instrument applied to a cupboard or cabinet door;

Figure 9 is a view of the instrument in flat compacted form for carrying in a tool box.

Referring specifically to the drawing, the invention in its present embodiment comprises a flat and generally triangular shaped metal body 10 having a laterally projecting and rectilinear gauging flange 11 along one edge thereof, and a slot 12 extending through the body from one edge thereof at a right angle to the flange.

A marker mounting member in the form of a flat bar 13 of metal is slidable in the slot 12 and can be rigidly secured in any selected position of

longitudinal adjustment to the body by means of knurled headed set screw 14 threaded into the body to bear against the bar.

Adjacent one end, the bar 13 has fixed thereto a marker in the form of a conical and pointed pin 15 which is adapted to co-act with an adjustable marker also in the form of a conical and pointed pin 16. The pin 16 is provided with a threaded shank 17 extending through a longitudinal slot 18 in the bar 13 and provided with a knurled nut 19 by which the pin 16 can be rigidly secured in any selected position of adjustment along the length of the slot 18. Upon tightening the nut 19, a shoulder 20 (Figure 5) between the pin and shank 17 is drawn against one side face of the bar 13, and a non-circular unthreaded portion 21 of the shank co-acts with the walls of the slot 18 to confine the marker against rotation. By this adjustment of the pin 16, the spacing between the two pins 15 and 16 can be varied to correspond with different distances between the screw holes in different types and sizes of handles.

Projecting from the outer side of the body 10 is an ear 22 having a bore 23 therethrough with its axis parallel to the length of the bar 13 and disposed for a prolongation of the axis to be in intersecting relation to the axes of the pins 15 and 16 so that in effect these three axes are in a common plane.

An arm in the form of a rod 24 is right angularly bent at one end to provide a pivot pin 25 rotatable freely in the bore 23; and in order to releasably retain the pin 25 against axial displacement from the bore, the pin has an annular groove 26 (Figure 4) adjacent its free end, into which a wire spring 27 is normally urged by being secured under stress to the body 10 by a screw 28 passing through a suitable eye in an end of the spring and threaded into the body.

The rod 24 constitutes a mounting for a gauging element co-actable with the gauging flange 11 and being in the form of a metal block 30 having a bore 31 therethrough slidably receiving the rod 24 for adjustment thereof along the length of the rod. A knurled headed screw 32 is threaded through the block 30 and is adapted to bear against the rod to rigidly secure the block in a selected position of adjustment on the rod.

As clearly shown in Figure 3, the gauging face 34 of the block 30 is relieved or inclined away from the rod at opposite sides of the rod, as shown at 35, to insure accurate fitting of the gauging face 34 on the edge of a drawer when the block is used at right and left side of the drawer at the

same adjustment of the block as will be more fully described in the operation of the instrument, which is as follows:

To use the instrument on a number of drawers 5 of the same size which are each to have a single handle applied thereto, the marking pin 16 is first adjusted on the bar 13 to a center to center distance from the marking pin 15 corresponding to the spacing between the screw holes in the 10 handle. The body 10 is now adjusted on the bar 13 for the two marking pins to be located for marking of the drawer front equidistantly at opposite sides of the vertical center of the drawer front when the inner face of the gauging flange 15 13 is held firmly against a side edge of the drawer front as indicated in Figure 6. The gauging block 30 is adjusted on the rod 24 for the gauging face 34 of the block to engage the top edge of 20 the drawer front when the marking pins are located for marking the drawer front, medially between its top and bottom edges, as shown in Figure 6, or at any other desired height on the drawer front.

With the instrument applied to the drawer 25 front as shown in Figure 6, sufficient pressure is exerted against the marking pins 15 and 16 for them to penetrate the drawer front and thus mark the location thereon to be drilled through for the handle securing screws. This operation 30 is, of course, repeated on all drawer fronts on which the handles are to be identically located, from which it will be clear that accurately level and uniform locating of all handles can be easily and quickly obtained.

To use the instrument on a drawer to which 35 two handles are to be applied as shown in Figure 7, suitable adjustment of the marking pin 16 is made to first obtain the exact center to center distance between the pins 15 and 16 corresponding 40 to the spacing of the screw holes in the handles. The body 10 is adjusted on the bar 13 to dispose the marking pins at the desired distance from one side edge of the drawer front, and the gauging block 30 is adjusted on the rod 45 24 to dispose the marking pins at the desired height on the drawer front, all as shown in the full line position of the instrument in Figure 7.

The drawer front is now marked by the pins 15 and 16, and the instrument removed from 50 the drawer front and reapplied thereto at the opposite side thereof as shown in broken lines in Figure 7, it being necessary in order for the gauging block 30 to function in this new position of the instrument, that the rod 24 be swung 55 about its pivot pin 25 through one hundred eighty degrees to dispose the gauging block 30 for engagement with the top edge of the drawer front in such new position of the instrument, and thus enable the drawer front to be marked at the identical height for both handles.

In the use of the instrument for marking cupboard or cabinet doors, the instrument is applied thereto as shown in Figure 8, in which use the marking block 30 is not needed, as the trained 65 eye is sufficient to locate the arm 13 centrally across the narrow width of the door stile, as is apparent from this figure.

When not in use, the rod 24 can be removed 70 from the body 10 by withdrawing the pivot pin 25 from the bore 23 after raising the spring 27 clear of the groove 26. The body 10 is moved 75 along the bar 13 a sufficient distance to clear one end of the rod 24 when the pivot pin 25 at the other end thereof is inserted into an opening 36 (shown in Figure 1) through the bar 13 and

the rod is disposed parallel to the bar, following which the body 10 is reversely shifted on the bar 13 until said one end of the rod 24 passes through the bore 23 of the ear 22. The set screw 14 is now tightened to secure the body and rod 5 against displacement. In this position of adjustment shown in Figure 9, the instrument forms a flat compact parcel for carrying in the tool box.

What is claimed is:

1. A gauging and marking instrument for drawer pulls and door handles comprising a body having a gauging portion adapted to rest against an edge of a drawer front at one side thereof; marking means; means mounting said marking means on the body at a distance from said gauging portion; and means co-actable with said body and adapted to co-act with an edge of the drawer front at a right angle to the first said edge thereof, to gauge the distance of the marking means from the second said edge of the drawer front. 10

2. A gauging and marking instrument for drawer pulls and door handles comprising a body having a gauging portion adapted to rest against an edge of a drawer front at one side thereof; marking means; means mounting said marking means on the body at a distance from said gauging portion; a gauging element; and means mounting said gauging element on the body for adjustment relatively thereto, and co-action with an edge of the drawer front at a right angle to the first said edge thereof, to adjustably gauge the distance of the marking means from the second said edge of the drawer front. 20

3. A gauging and marking instrument for drawer pulls and door handles comprising a body having a gauging portion adapted to rest against an edge of a drawer front at one side thereof; marking means; means mounting said

marking means on the body at a distance from said gauging portion; a gauging element; means mounting said gauging element on the body for adjustment relatively thereto, and co-action with an edge of the drawer front at a right angle to the first said edge thereof, to adjustably gauge the distance of the marking means from the second said edge of the drawer front; and means mounting the gauging element for movement from a gauging position at one side of the marking means to a gauging position at the other side thereof, with the distance of the gauging element from the marking means maintained unchanged for use of the instrument in a reversed position at the opposite side of the drawer front. 35 40 45 50 55

4. A gauging and marking instrument for drawer pulls and door handles comprising a body having a gauging portion adapted to rest against an edge of a drawer front at one side thereof; marking means; means mounting said marking means on the body at a distance from said gauging portion; a gauging element; a rod on which the gauging element is mounted for adjustment along the length of the rod; and means mounting said rod on the body for pivotal movement 60 65 70 75 80 85 90 95 from a gauging position wherein the gauging element is co-actable with an edge of the drawer front at a right angle to the first said edge thereof, to a gauging position wherein the gauging element is identically co-actable with the same edge of the drawer front in a reversed position of the instrument at the opposite side of the drawer front.

5. A gauging and marking instrument for drawer pulls and door handles comprising a body 75

having a laterally projecting gauging flange adapted to rest against an edge of a drawer front or door at one side thereof; a bar slidably mounted on the body for longitudinal adjustment at a right angle to the length of said flange; marking means on said bar; and means co-actable with said body and adapted to co-act with an edge of a drawer front or door at a right angle to the first said edge thereof, to gauge the distance of the marking means from the second said edge.

6. A gauging and marking instrument for drawer pulls and door handles comprising a body having a laterally projecting gauging flange adapted to rest against an edge of a drawer front or door at one side thereof; a bar slidably mounted on the body for longitudinal adjustment at a right angle to the length of said flange; marking means mounted on said bar; an arm pivotally mounted on the body for movement in a path parallel to the length of said flange from one side of the bar to the other; and a gauging element mounted on said arm for adjustment along the length thereof.

7. A gauging and marking instrument for drawer pulls and door handles comprising a body having a laterally projecting gauging flange adapted to rest against an edge of a drawer front or door at one side thereof; a bar slidably mounted on the body for longitudinal adjustment

at a right angle to the length of said flange; marking means mounted on said bar; an arm pivotally mounted on the body for movement in a path parallel to the length of said flange from one side of the bar to the other; and a gauging element mounted on said arm for adjustment along the length thereof, said gauging element having a gauging face which is inclined or relieved from a point at the arm to opposite free edges of the gauging element for the purpose described.

8. A gauging and marking instrument of the class described comprising a body having a gauging portion adapted to engage and be guided rectilinearly against an edge of a drawer front or door; a plurality of screw hole marking elements; means mounting said elements from the body for relative adjustment in one and the same straight line at a right angle to the engaging surface of said portion, for marking of the drawer front or door at predetermined distances from said edge thereof and means co-actable with said body and adapted to co-act with an edge of the drawer front at a right angle to the first said edge thereof, to gauge the distance of the marking elements from the second said edge of the drawer front.
